(57) CLAIM

The ornamental design for a shirt and tie arranged in a box, as shown and described.

DESCRIPTION

FIG. 1 is a top plan view of a first embodiment of a shirt and tie arranged in a box showing my new design;

FIG. 2 is a front elevation view thereof;

FIG. 3 is a rear elevation view thereof;

FIG. 4 is a bottom plan thereof;

FIG. 5 is a left side elevation view thereof;

FIG. 6 is a right side elevation view thereof; and

FIG. 7 is a top plan view of a second embodiment of the shirt and tie arranged in a box.

FIG. 8 is a front elevation view thereof;

FIG. 9 is a rear elevation view thereof;

FIG. 10 is a bottom plan thereof;

FIG. 11 is a left side elevation view thereof; and,

FIG. 12 is a right side elevation view thereof.

The broken lines of FIGS. 1–12 are for illustrative purposes only and form no part of the claimed design. All sides not shown form no part of the claimed design.
